AUTOMATIC LIGHTING MEANS FOR GAS STOVES

Filed Sept. 29, 1926

Inventor
Jacob Copilovich

By *Jacob Copilovich*

Attorney

UNITED STATES PATENT OFFICE.

JACOB COPILOVICH, OF ST. PAUL, MINNESOTA.

AUTOMATIC LIGHTING MEANS FOR GAS STOVES.

Application filed September 29, 1926. Serial No. 133,412.

My invention relates to means for automatically operating the pilot light or flasher on a gas stove which is ordinarily now operated by hand. The pilot light is of ordinary well known construction now in use, whereby by pressing a button the pilot light is flashed to the burners on the gas stove, and then by a separate operation turning on the gas, the burner is lit from the pilot light.

My invention relates to an automatic lighter for gas stoves adapted to operate by the turning of the gas automatically in a manner to project the flame from the pilot light to the burners, lighting the turned on burner immediately. This provides a safeguard to a gas stove so that the burners cannot be turned on without the same. This is an important feature of my invention as gas stoves are quite dangerous in the home where there are children, and often the burners are turned on by the child, who, not being aware of the danger, does not turn on the lighter at the same time that the gas burner is turned on, and thus gas escapes into the home which may become very dangerous before it is apprehended by the parent and turned off.

With my invention this difficulty is entirely overcome as the burner cannot be turned on without lighting the same automatically. After the burner valve is opened, by means of a cam member adjustably connected to the valve, I cause the lighter pilot to be automatically operated momentarily, which is just sufficient to flash the lighting flame to the particular burner turned on and thereby automatically lighting the burner, overcoming any danger or possibility of the burner being turned on without lighting it, thus safeguarding the home from asphyxiation by gas when the burners are turned on accidentally by a child or otherwise.

My invention includes means of a simple nature and of an inexpensive design which may be attached to practically any gas stove now equipped with a pilot lighter, or which can be equipped with a flasher so that the same may be made to operate automatically, the parts being adjustable to the particular valve and lighter mechanism. In this manner I provide a very practical device for automatically lighting gas burners.

These objects, together with other details and features of the invention will be more

clearly and fully set forth in the specification and claim.

In the drawings:

Figure 1 is a perspective view of a portion 60 of a gas stove showing my invention attached thereto.

Figure 2 is an enlarged detail of a portion 65 of a gas stove in dotted outline and showing my invention associated with the gas valve which is adapted to turn the gas on and off from the feed pipe and associated with the operating valve of a pilot light or flasher.

Figure 3 is a plan view of a portion of 70 my device.

Figure 4 is a side view of my device associated with the gas valve.

Figure 5 is a bottom view of the gas valve and the associating parts of my device. 75

In the drawings I have illustrated a gas stove A, only a portion of which is shown, to illustrate the position of the burners B which are ordinarily lit by means of matches or may be lit by a pilot light such as C, approximately centrally positioned between the burners and having openings to permit a flame to be flashed or projected to each burner when the pilot light valve 10 is operated. The pilot light illustrated is not 80 shown in its minute detail because it is of any ordinary and well known construction wherein a small pilot light is employed which burns continuously and which is adapted to flash or project a flame when the 85 valve 10 is pressed down to open the same.

In the ordinary gas stoves such as A, the burners B are fed by a main supply pipe 11 which extends along the front of the stove and from which the gas valves 12 project so 90 as to direct the gas to the burners B. These valves 12 are provided with operating handles 13 to turn them on and off. The valves 12 are ordinarily formed with a lower projecting portion or shank 14 which carries a spring 15 and adjusting nut 16. This permits the adjustment of the valve 12 to take up any wear and to keep the valve held under spring tension in operating position. In carrying out my invention I provide a 100 cam member 17 which is provided with a downwardly projecting cam lip 18 and which is adjustably held to the shank by the nut 19 which causes the cam member to be firmly attached to the shank against the nut 110 16. Thus when the handle 13 is operated the cam lip 18 is operated so that simul-

taneously with the opening or closing of the valve 12 by the handle 13, the cam lip 18 is operated, the purpose of which will be hereinafter described.

5 The pilot or flasher C is connected by the feed pipe 20 which leads from the valve 10 to the flasher head 22, while the valve 10 is connected directly to the gas supply pipe 11. The valve 10 is provided with an operating head or button 23 which is ordinarily held by a spring means, not illustrated in the drawings, in practically closed position. When the button 23 is depressed an increase supply of gas is projected through the pipe 10 to the head 22 in a manner to cause the pilot C or flasher to project a flame to each of the burners B. I provide a yoke arm 24 which is adapted to extend over the button 23 and which carries a strap member 25 across the top of the same. The strap member 25 is formed with bifurcated ends that form lips 26 which may be bent below the button 23 to attach the yoke 24 firmly to the operating button 23, as illustrated in Figures 2 and 3.

15 The downwardly depending ends 27 of the yoke 24 are attached to the operating rod 28 which extends along below the valves 12, and which is positioned adjacent the cam 20 lips 18 which are attached to each of the valves 12 as hereinbefore described. The rod 28 is formed with downwardly depending outer ends 29 which extend through guide members 30 and which carry coil 30 springs 31 above the guide members and at the corner 32 of the rod 28.

35 The coil springs 31 assist in holding the rod 28 elevated to normally hold the valve 10 approximately closed as is ordinarily the case with the pilot light C. The springs 31 are not always necessary as I have found my automatic lighter will operate without these coil springs, but I desire to illustrate them that it may be clear that such springs 45 may be used to assist in holding the rod 28 out of operating position. The depending end 29 of the rod 28 extends freely through the guide member 30.

50 When the valve 12 is operated by the handle 13, the cam lip 18 is caused to rotate into the path of the rod 28 depressing the same, drawing the yoke 24 downward against the button 23 to flash the pilot C to the burners B. Therefore it will be readily apparent that my automatic gas lighter 55 operates in a very simple effective manner, causing the pilot to operate simultaneously with the valves 12 and not permitting any of the burners to be turned on without lighting the same from the pilot or flasher C.

60 The operation of the pilot or flasher C is

automatic with the operation of the valve 12 and is only momentarily, as the cam lip 18 engages the rod 28 to press the same downward in a manner to operate the button 23 65 and to automatically release from the rod 28 after the cam lip 18 has passed over the rod and the burner valve 12 is in open position. The cam 17 with the lip 18 is so positioned in relation to the rod 28 that the 70 valve may be partially closed to turn down the burner without operating the pilot. This is also true in the opening of the burner as it is apparent that none of the valves 12 operate sufficiently to leak gas 75 until they have been turned a certain distance. The cam 17 is adjustable so that it may be properly set in relation to the rod 28.

80 The simple effective operation of my automatic lighter for gas stoves is quite apparent and the structure of the same is simple, being readily connectible to the present pilot lights which are now in use on gas stoves of well known construction, so that at a small cost any gas stove can be equipped 85 with my automatic lighter means and thereby prevent the accidental leakage of gas, because with my lighter when the burner is turned on the gas will be lit. I have found my device to be very practical in use and 90 to be preferred, as it may be operated with a single hand, not making it necessary to used both hands when the burner is turned on, as is ordinarily the case where the ordinary pilot light is used. I believe my automatic lighter also saves gas as it only lights 95 the pilot when it is needed and this is momentarily so that only a small amount of gas is consumed in operating the same.

100 In accordance with the patent statutes I have described the principles of operation of my automatic gas lighter and I have illustrated in the drawings a particular attachment and construction of the same, however, this is only illustrative of a means of carrying out my invention and it is apparent that it may be applied to uses other than those above set forth and carried out by other means within the scope of the following claim.

110 I claim:

A lighter for gas stoves having burner valves and a pilot light valve, comprising a vertically movable longitudinally disposed rod, a loop fastened to said rod having a 115 flat portion which is adapted to rest upon said pilot light valve and support said rod therefrom and means carried by each of said burner valves for depressing and releasing said rod during operation of said burner 120 valves in one direction.

JACOB COPILOVICH.
